INVENTOR:
Joseph B. Strauss
By Parker + Carter ATTYS

UNITED STATES PATENT OFFICE

JOSEPH B. STRAUSS, OF CHICAGO, ILLINOIS

BRIDGE

Application filed February 29, 1924. Serial No. 695,879.

This invention relates to improvements in bascule bridges and has for its object to provide a new and improved bridge of this description. The invention has as a further object to provide a means for supporting the movable leaf which shall be economical and efficient. The invention has as a further object to provide a counterweight construction for the movable leaf. The invention has further objects which are more particularly pointed out in the accompanying specification.

Referring now to the drawings:

Fig. 1 is a view showing a side elevation in part section of one form of device embodying the invention.

Fig. 2 is a sectional view on line 2—2 of Fig. 1 with parts omitted.

Fig. 3 is a sectional view on line 3—3 of Fig. 1 with parts omitted.

Fig. 4 is a sectional view taken on line 4—4 of Fig. 1, with parts omitted.

Fig. 5 is a sectional view taken on line 5—5 of Fig. 1 with parts omitted.

Like numerals refer to like parts throughout the several figures.

Referring now to the drawings, I have shown a cantilever leaf section or bascule leaf 1 provided with trusses 2 at opposite sides thereof. Each truss is provided with a trunnion 3 which projects on each side thereof (see Fig. 3). Each truss, that is each trunnion, has an outside support and an inside support, the truss being between these supports. The outside supports consist of posts 4 which are suitably braced by the forward braces 5 and the lateral braces 4^a. There is a front or live load support 6 which engages the truss as shown in Fig. 1, and takes the live load, and which is connected with the posts 4. The inside support for each trunnion consists of a longitudinal, diagonal supporting member 7 (see Figs. 1 and 2) which has its lower end connected to the live load support 6 and the outside posts 4 by means of the connecting members 8. The upper ends 7^a of the longitudinal, inclined inside supports are preferably horizontal and are supported upon the support 9. The

trunnions are provided with suitable bearing 3^a which are connected with these outside and inside supports. The tail end of the leaf projects beyond the trunnions and a counterweight 10 is connected therewith. This counterweight is preferably of concrete and is provided at each side with slots 11 for the posts 4 of the outside supports. The bottom of these slots are indicated by dotted line 11^a, Fig. 1. The counterweight is also provided with slots for the inside trunnion supports 7. When the bridge is closed the upper portion 12 of the slot receives the horizontal portion 7^a of the inside support and a part of the inclined portion as clearly shown in Fig. 1. When the bridge is open the lower portions 12^a of the slots receive the inclined portions 7 of the inside supports. The bottom of the slots for the inside supports are indicated by dotted line 12^b of Fig. 1. It will thus be seen that there is no interference between the stationary parts and movable parts for when the leaf is closed, (as in Fig. 1) the upper ends of the inside supports enter the slots 12 in the counterweight and when the bridge is lifted the posts 4 enter the slots 11 in the counterweight and the inclined portion of the inside supports enter the lower portion 12^a of the slots in the counterweight. Connected with the trusses 2 is a rack 13 which is engaged by pinions 14 mounted on the driving shaft which is driven by any suitable motor (not shown). There may be two racks 13 and two pinions 14, one for each truss. An approach floor 15^a is supported upon suitable supports. In the construction shown the pier has a front wall 16 and a rear wall 17 and the inclined inner trunnion support which may be a truss, girder or the like, extends from a point in front of the trunnion to the rear wall, the front end being preferably connected with the outer limit of the outside support as by means of the member 8. The counterweight 10 is rigidly connected by the main trusses 2 and has cantilevered ends extending laterally beyond the trusses. It will be seen that the various slots in the counterweight required for the inside and outside supports for the trunnions leave a solid central portion extending across from

truss to truss, and it will further be seen that these slots being at different points along the counterweight permit the members of the trusses to be embedded therein as shown in Fig. 4, the ends of the counterweight at each side projecting beyond these trusses. This gives a large space for a large bulk, light weight counterweight such as that made from concrete. The outside supports it will be noted are triangular shaped, each having vertical, horizontal and inclined members, the vertical live load supporting member being connected with the inclined member, there being cross connection between said inclined member and said vertical live load supporting member, said cross connection being located above the bottom of the supporting member.

I claim:

1. A bascule bridge comprising two separated trusses, trunnions for said trusses, outside supports upon which one end of each of said trunnions is mounted, means associated with said supports for resisting the vertical, longitudinal and transverse forces thereon, an underneath concrete counterweight located under the roadway and extending between the trusses and comprising a top portion rigidly connected to the ends of the trusses, and portions projecting outwardly and laterally from said rigidly connected portion and cantilevered therefrom, said cantilevered portions being provided with means to clear said outside supports when the bridge is open.

2. A bascule bridge comprising a pier having a front and rear wall, trunnions for said trusses, supports for said trunnions, one outside and one inside each truss, the inner support comprising a longitudinal member extending from a point in front of the trunnion to the rear wall of the pier, the outer support extending vertically from the trunnion to the pier, and a supporting member for said vertical support to take the horizontal forces on the trunnion.

3. A bascule bridge comprising a pier having a front and rear wall, trusses for said trunnions, supports for said trunnions, one outside and one inside each truss, the inner support comprising a longitudinal member extending from a point in front of the trunnions to the rear wall of the pier, the outer support extending vertically from the trunnion to the pier, and a supporting member for said vertical support to take the horizontal forces on the trunnion, the trunnion supports taking the dead load reactions from the trusses, and a part formed on the front end of the trunnion supports to take the live load reactions from the trusses.

4. A bascule bridge comprising a pier having a front and rear wall, trusses on which said trunnions are mounted, supports for said trunnions, one outside and one inside

each truss, the inner support being a longitudinal member extending from the outer limit of the outside support to the rear wall of the pier, the outer support extending vertically from the trunnion to the pier, and a supporting member for said vertical support to take the horizontal forces on the trunnion, the supporting member and the truss extending forward of the trunnion and connecting to a supporting part for the live load reactions from the trusses.

5. A bascule bridge comprising two separated trusses, a concrete counterweight extending across the space between the trusses and rigidly connected to the ends thereof, said counterweight having cantilevered ends which project beyond the trusses, trunnions for said trusses, inclined longitudinal inside supports for said trunnions and slots in said counterweight for receiving said inside supports both when the main span is open or closed.

6. A bascule bridge comprising two separated trusses, a concrete counterweight extending across the space between the trusses and rigidly connected to the ends thereof, said counterweight having cantilevered ends which project beyond the trusses, trunnions for said trusses, inclined longitudinal inside supports for said trunnions and slots in said counterweight for receiving said inside supports both when the main span is open or closed, outside supports for said trunnions, the cantilevered ends of said counterweight having slots to receive said outside supports.

7. A bascule bridge comprising trusses, trunnions therefor, supports on the outside and the inside of the trusses for said trunnions, said inside supports comprising inclined longitudinal members, the rear ends of said members bent at an angle to the inclined portions.

8. A bascule bridge comprising separated trusses, trunnions therefor, supports for said trunnions, a counterweight extending across the space between the trusses and projecting laterally at each end therefrom, the cantilevered portions of said counterweight having two slots at each end thereof on opposite sides of the trusses to receive the supports for the trunnions of the bridge as the latter is moved to different positions.

9. A bascule bridge comprising two separated trusses, trunnions therefor, inside and outside supports for said trunnions, each outside support comprising a triangular shaped member, made up of vertical horizontal and inclined members, a vertical live load supporting member connected with the incline member of said support and a cross connection between said incline member and said vertical live load supporting member.

10. A bascule bridge comprising separated trusses, trunnions therefor, inside and outside supports for the trunnions, each inside

support comprising a longitudinal member having an inclined portion which extends underneath the trunnions and a horizontal portion and a support for said horizontal portion.

- 5 11. A bascule bridge comprising separated trusses, trunnions therefor, inside and outside supports for the trunnions, each inside support comprising a longitudinal member having an inclined portion which extends underneath the trunnions and a horizontal portion and a support for said horizontal portion, a counterweight connected with said trusses, said counterweight having slots at the top thereof for the horizontal portions of the inside supports and slots at the front and bottom thereof for the inclined portions of said inside supports.
